UNITED STATES PATENT OFFICE.

CARLO BONIFORTI, OF MILAN, ITALY.

CUT-FILM PACK.

Application filed July 10, 1925, Serial No. 42,714, and in Italy July 30, 1924.

This invention relates to film packs and more particularly to a pack of cut films each in a separate sheath adapted to be placed in a magazine in a camera.

5 In my improved film pack I have taken advantage of the natural resilience of the paper forming the sheaths and form this into a flange embracing one edge of the film. The natural tendency of the paper to 10 straighten out causes the end of the pack wherein the flanges are to tend to expand, thus causing the pack to fill the space allotted to it in a magazine and causing the 15 films to tend to separate with a resulting slight space between them that is readily engaged by the end of a septum of a magazine. The invention to which this application particularly relates resides in the individual members and in a pack of such 20 members. The magazine with which this pack is particularly useful is disclosed in my copending application Serial No. 42,713, filed July 10, 1925.

Reference will now be made to the accompanying drawing wherein the same reference characters refer to the same parts throughout, and in which—

Fig. 1 is a perspective view of a pack of films embodying my invention.

30 Fig. 2 is a section on line 2—2 of Fig. 1.

Fig. 3 is a perspective view of the top protective sheet.

Fig. 4 is a perspective view of a single sheath.

35 Fig. 5 is a perspective view of a single cut film, and

Fig. 6 is a side view of a portion of a pack showing how it tends to expand when held at the middle.

40 My improved film pack consists of a series of cut film sheets 1, each having a sheath 2, with a dummy sheet 3 at the bottom, and a protective sheet 4 above the top film, the whole being held together during shipment by a paper band or the like 5. This pack will be enclosed in a suitable light tight packing for shipment and storage, and, as the outside wrapper may assume any convenient form or design, being no part of my present 45 invention, it is not shown.

50 Each cut film sheet 1 is of the usual rectangular form and is accompanied by a sheath 2, comprising a backing sheet 6 of the size of the film 1 and having at one end 55 a turned over flange 7. As the sheath is

ordinarily made of paper there is a natural tendency of the flange to straighten out. The film is not ordinarily attached to the sheath but one end merely lies under the flange. The top protective sheet 4 is usually 60 a piece of paper having a tab 8 cut out from it in the manner shown.

When the package has been opened and the band 5 broken, the protective sheet 4 is removed by the tab 8 and the remaining 65 pack placed in the magazine designed for it. This pack usually includes a bottom dummy member 3 of stiff material such as heavy cardboard which gives rigidity to the pack, protects it and serves to indicate when 70 all the films have been used. The end of the member 3 under the flanged ends of the sheath is bevelled at 10 to assist in its co-operation with the magazine septum. As was noted above the flanges 7 having a tendency to straighten out and the cumulative effect of this in all the flanges is to cause 75 this end of the pack to expand as shown in Fig. 6, wherein there is also shown a band 9 encircling the pack transversely. This 80 tendency to expand causes wedge shaped openings 11 to be formed between successive sheaths, which renders easier the entrance of a septum of a magazine. The pack tends to fill a magazine with which it is used and 85 it is possible to expose some of the films and remove them in a darkroom, whereupon the expansive tendency of the flanges causes the remaining sheaths to fill the magazine in an operative manner. 90

It is to be understood that the embodiment herein disclosed is by way of example and I contemplate as included within my invention all such modifications and equivalents as fall within the scope of the appended 95 claims.

Having thus described my invention, what I claim as new and desire to secure by Letters Patent is:

1. In combination, a cut film sheet and a 100 sheath therefor, the sheath comprising a sheet of flexible material underlying said sheet and having at one end only a flange loosely embracing the corresponding end of the sheet and unattached to the sheet. 105

2. In combination, a cut film sheet and a sheath therefor, the sheath comprising a sheet of flexible material underlying said sheet and having at, at least, one end a flange embracing the corresponding end of 110

the sheet, the material of the sheath having resilience causing the flange to have a tendency to straighten out.

3. In combination, a rectangular cut film sheet and a sheath therefor, the sheath comprising a sheet of paper underlying said sheet of paper and unattached thereto and having at one end only a flange embracing the corresponding end of the sheet, the natural resilience of the paper causing the flange to tend to straighten out.

4. A pack of cut films designed for use in a camera magazine and comprising a plurality of cut film sheets and a plurality of sheets separating said film sheets, there being in the pack resilient means, at least part of which is between the films, tending to expand whereby the film sheets tend to be separated.

20 5. A pack of cut film designed for use in a camera magazine and comprising a plurality of cut film sheets and a plurality of sheaths separating said film sheets, said separating sheets being formed of material having a natural resilience and having a part thereof formed to constitute expansive members tending to separate the sheets and to expand the pack as a whole.

6. A pack of cut films designed for use in a camera magazine and comprising a plurality of cut film sheets and a plurality of sheaths therefor, each sheath comprising a sheet of flexible material underlying the corresponding sheet and having at one end only a flange embracing the corresponding end of the corresponding sheet.

7. A pack of cut films designed for use in a camera magazine and comprising a plurality of cut film sheets and a plurality of sheaths therefor, each sheath comprising a sheet of flexible material underlying the corresponding sheet and having at, at least, one

end a flange embracing the corresponding end of the corresponding sheet, the material of the sheaths having resilience causing the flanges to tend to straighten out and thereby to separate the film sheets.

8. A pack of cut films designed for use in a camera magazine and comprising a plurality of cut film sheets and a plurality of sheaths therefor, each sheath comprising a sheet of paper underlying the corresponding sheet and having at one end only a flange embracing the corresponding end of the sheet, the natural resilience of the paper causing the flanges to tend to straighten out and thereby to separate the film sheets.

9. A pack of cut films designed for use in a camera magazine and comprising a plurality of cut film sheets and a plurality of sheaths therefor, each sheath comprising a sheet of paper underlying the corresponding sheet and unattached thereto and having at, at least, one end a flange embracing the corresponding end of the sheet, the natural resilience of the paper causing the flanges to tend to straighten out and thereby to separate the film sheets.

10. A pack of cut films designed for use in a camera magazine and comprising a plurality of cut film sheets and a plurality of sheaths therefor, each sheath comprising a sheet of paper underlying the corresponding sheet and having at one end only a flange embracing the corresponding end of the sheet, the natural resilience of the paper causing the flanges to tend to straighten out and thereby to separate the film sheets, and a sheet of material of greater rigidity than the above mentioned sheets and beveled at that end that corresponds to the flanged end of the separating sheets.

CARLO BONIFORTI.
